UNITED STATES PATENT OFFICE.

HUBERT R. HUMPHREY, OF KALAMAZOO, MICHIGAN.

GAS STOVE.

Application filed September 3, 1921. Serial No. 498,306.

To all whom it may concern:

Be it known that I, HUBERT R. HUMPHREY, a citizen of the United States, residing at the city and county of Kalamazoo, State of Michigan, have invented certain new and useful Improvements in Gas Stoves, of which the following is a specification.

This invention relates to improvements in gas stoves. The main objects of this invention are:

First, to provide an improved operating means for multiple burner gas stoves in which gas may be admitted to all or a part of the burner members as desired.

Second, to provide in a gas stove of this type an improved igniting means.

Third, to provide an improved igniting means for gas stoves having radiating elements of foraminous earthy material.

Fourth, to provide an improved valve actuating and igniting means for gas stoves which is simple in structure and at the same time very efficient.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawings, forming a part of this application, in which:

Fig. I is a front elevation of a gas stove embodying the features of my invention, parts being broken away and other parts omitted to illustrate features of the invention; other parts being shown conventionally for convenience in illustration.

Fig. II is an enlarged detail fragmentary view of the burner and the burner valve operating means partially in section on line 2—2 of Fig. IV.

Fig. III is a fragmentary view similar to that of Fig. II, showing the electromagnet in its actuated position.

Fig. IV is a detail view of the valve partially in longitudinal section on a line corresponding to line 4—4 of Figs. II and V.

Fig. V is a plan view of the valve actuating means, the burner manifold being shown partially in horizontal section.

Fig. VI is a detail section on a line cor-

responding to line 6—6 of Fig. II, showing details of the valve actuating mechanism.

Fig. VII is a detail section through the valve on a line corresponding to line 7—7 of Fig. IV.

Fig. VIII is a detail section through the valve on a line corresponding to line 8—8 of Fig. IV.

Fig. IX is a detail vertical section on a line corresponding to line 9—9 of Fig. I, showing the arrangement of the igniter elements on the fireback.

Fig. X is a detail horizontal section on a line corresponding to line 10—10 of Figs. I and X.

Fig. XI is a diagrammatic view showing the electrical connections for the igniter and the valve actuating means.

In the drawings similar reference characters refer to similar parts throughout the several views, and the sectional views are taken looking in the direction of the little arrows at the ends of the section lines.

Referring to the drawings, 1 represents the frame or body of the stove, 2 the fire back which is arranged therein, and 3 the foraminated tubular radiating elements which are disposed in front of the fireback.

The fireback is preferably provided with an overhang 4 at its upper end, the upper ends of the radiating elements being adjacent to and under this overhang, as shown in Fig. IX.

The burner is of the general character of that shown in my application for Letters Patent, filed Aug. 3, 1920, Ser. No. 400,948, and consists of a plurality of independent burner tubes or members 5 each operatively associated with one of the radiating elements 3. The gas delivery nozzles 6 are mounted upon the manifold 7 so as to deliver to the lower ends of these tubes. The manifold has a chamber 8 with which a part of the nozzles 6 are connected and a chamber 9 with which the remaining tips are connected.

The casing has ports 12 connecting with the manifold chamber. The valve 13 is rotatable in the casing and is provided with a longitudinal bore or passage 14 communicating with the supply pipe. The valve has ports 15 and 16,—see Figs. IV, VII and VIII, adapted to be brought into register with the casing ports 12. The port 16 is elongated so that while both ports are simultaneously opened the port 15 is cut off

prior to the closing of the port 16. This delivers gas to all of the burner members when the valve is actuated to open the same. The second actuation cuts off a part of the burner members and a third actuation cuts off all of the burner members.

In the structure illustrated this is accomplished by means of an electromechanical mechanism consisting of an electromagnet 10 17, the armature 18 of which is connected to the pawl carrier 19 by means of the link 20. A coiled spring 21 returns the armature when the current is cut off.

The pawl carrier 19 is rotatably mounted 15 on the stem 22 carrying a sleeve 23 rotatable therewith. On this sleeve is a ratchet wheel 24 and a stop wheel 25. The pawl 26 is of the reciprocating type being held yieldingly in engagement with the ratchet wheel by the 20 spring 27,—see Fig. VI.

The link 20 has an extension 28 coating with the stop ratchet 25 preventing overthrow of the valve. The valve stem is also provided with a hand wheel 29 so that the 25 valve may be manually manipulated if desired,—see Fig. IV.

With this arrangement, on each actuation of the electromagnet the valve is advanced one step, the ports being arranged, 30 as stated, so that on one actuation both ports are opened. On the next actuation port 15 is cut off and the port 16 still remains open, thereby supplying gas to a part only of the burner members, and on the succeeding actuation gas is cut off from all of the burner members.

I arrange an igniter, designated generally by the numeral 30, in a recess 31 in the fireback adjacent the upper ends of the radiating elements and below the overhang 4 of the fireback. This igniter, in the structure illustrated, is a resistance wire wound upon a suitable core. The igniter is connected by the wires 32 in series with the electromagnet, 40 as shown diagrammatically in Fig. XI, the circuit 33 being controlled by a switch 34 automatically opened by the spring 35 so that when the switch 34 is held closed by the operator the armature is actuated and 45 current is supplied to the igniter, the current being supplied as long as the switch is held open, it being automatically cut off upon releasing the switch. This enables the operator to maintain the current on the igniter until the same is heated sufficiently to 50 light the gas.

By positioning the igniter as I have described, the gas is turned on and flows up

through the radiating elements below the fireback and a suitable igniting mixture is 60 secured so that the burners are lighted without producing an objectionable explosion such as is likely to occur where an attempt is made to light the burners instantly upon turning on the gas or at the burner tips, the 65 slight lapse of time required for the igniter to become incandescent being sufficient for the gas to reach the top of the radiating elements and to form a proper lighting mixture.

I have illustrated and described my improvements in an embodiment which I find highly satisfactory. I have not attempted to illustrate or describe certain modifications and adaptations which I contemplate 70 as I believe the disclosure made will enable those skilled in the art to which my invention relates to embody or adapt the same as may be desired.

Having thus described my invention, what 80 I claim as new and desire to secure by Letters Patent, is:

1. In a structure of the class described, the combination of a fireback, radiating elements disposed at the front thereof, a burner operatively associated with said radiating elements, a gas supply valve, an electrically controlled actuating means for said valve, and an igniter element disposed on said fireback and connected to said valve 85 control means so that current is supplied to the igniter element upon the actuation of the valve.

2. In a structure of the class described, the combination of a fireback, radiating elements disposed at the front thereof, and an igniter disposed in a recess in said fireback adjacent the upper ends of said radiating elements.

3. In a structure of the class described, the combination of a fireback having an overhang at the top, a plurality of tubular foraminated radiating elements disposed against the face of said fireback with their upper ends adjacent said overhang, and an igniter disposed on said fireback below said overhang and adjacent the upper ends of said radiating elements.

In witness whereof, I have hereunto set my hand and seal in the presence of two 110 witnesses.

HUBERT R. HUMPHREY. [L. S.]
